UNITED STATES PATENT OFFICE.

CLARENCE H. YOUNG, OF BOSTON, MASSACHUSETTS.

BED-HAMMOCK.

1,030,960.

Specification of Letters Patent. Patented July 2, 1912.

Application filed November 16, 1911. Serial No. 660,576.

To all whom it may concern:

Be it known that I, CLARENCE H. YOUNG, a citizen of the United States, and a resident of Boston, in the county of Suffolk and 5 Commonwealth of Massachusetts, have invented certain new and useful Improvements in Bed-Hammocks, of which the following is a full and clear specification.

The object of this invention is the construction of means for readily converting a bed hammock into a swing seat, having a back of any desired angle, height and position. To this end, I prefer to provide a canvas back stiffened by means of two or more 15 longitudinally extended bars, and adapted to be supported by the end wind-shields of the bed hammock.

Referring to the drawings forming part of this specification, Figure 1 is a perspective view of a combined swing seat and bed hammock embodying my invention. Fig. 2 is a detail view nearly full size, of one end of one of the stiffening bars, together with a section of the canvas back, and showing the 25 terminal attaching means. Fig. 3 is a cross section of said bar. Fig. 4 is a detail view of a locking pin.

The bed hammock illustrated comprises a mattress 1 of any usual construction and 30 provided with any usual supporting or stiffening frame 2, having end windshields 3 suspended by suitable cords or other means 4.

In place of the customary side wind-shield, I provide a canvas back 5 of a length 35 to fit between the end wind shields, and preferably of the same height as the latter. Along the top edge of said back is a hem 6 within which is a bar 7 preferably of wood 40 and flattened as shown in Fig. 3. Midway of said back is a similar bar 9 suitably fastened thereto by a hem or seam; both bars extending the entire length of said back, and from each of their ends projects a pin 10 45 having an eye 11 at its extremity. These pins being introduced through certain of the gromets 12 arranged in the end windshields, as shown in Fig. 1, and then the pins 13 (Fig. 4) inserted in said eyes to retain said parts in place, the bed hammock is 50 ready for use as a swing seat.

As illustrated, the lower bar 9 is arranged in advance of the upper bar 7 in order to give the back sufficient inclination for comfortable sitting; and extra holes or gromets

12 are provided in front of the others so that little folks with short legs use the swing seat equally well, by simply locating the back nearer the front edge of the mattress. Said bars need, of course, to be sufficiently inflexible to sustain the pressure of those who may sit on the seat and lean against the back, but such pressure is not excessive. When using the back as a rear windshield, the bars 7, 9 are engaged in the 60 topmost and middle gromets of the end wind-shields, while the loose lower section of the back may be tied in place by tapes or cords 14 in the usual manner. On this account, it is advisable to have the gromets spaced equally, so that the middle one in each end windshield is substantially half way between the top and bottom ones, and to dispose the bars 7, 9 at equal distances 65 from each other. I find that the cotter pins so frequently used are not at all convenient to insert in the eyes 11, and I therefore employ the much more easily introduced pins 13 shown in Fig. 4. These consist each of a single length of wire having the upper section bent over upon the lower, the upper section 15 having a semi-circular curve 16 for engaging the member 10 and locking the pin 13 against too easy withdrawal. By furnishing two of these stiffened backs, one 70 for each side of the bed hammock, the same 75 can be used for infants, making a perfectly 80 safe crib for them.

What I claim as my invention and for 85 which I desire Letters Patent is as follows, 90 to wit;—

1. The combination with a bed hammock having fabric end windshields, of a back comprising a fabric having two parallel longitudinal extended spaced stiffening 95 bars, and means for terminally connecting said bars to said end windshields at points of the latter to support both the upper part and the lower part of the back of a person 100 sitting upon the bed hammock.

2. The combination with a bed hammock having end wind-shields provided with gromets, of a back comprising a fabric having longitudinal stiffening bars, pins projecting from said bars and adapted to enter certain of said gromets, and means for locking said pins therein.

3. The combination with a bed hammock having end wind-shields provided with 105 equally spaced holes along their rear verti- 110

cal edge, and other holes in front thereof, of a back comprising a fabric provided with stiffening bars at the top edge and mid-height thereof, pins projecting from said bars adapted to enter certain of said holes, and means for locking said pins in said holes.

In testimony that I claim the foregoing invention, I have hereunto set my hand this 14 day of November, 1911.

CLARENCE H. YOUNG.
